CLAIM

The ornamental design for a syringe plunger, as shown and described.

DESCRIPTION

FIG. 1 is a bottom perspective view of a syringe plunger showing our new design;

FIG. 2 is a bottom view thereof;

FIG. 3 is a front elevation view thereof, the rear elevation view being a mirror image thereof;

FIG. 4 is a left side elevation view thereof, the right side elevation view being a mirror image thereof;

FIG. 5 is a longitudinal cross-sectional view thereof taken along line 5-5 shown in FIG. 2; and,

FIG. 6 is a latitudinal cross-sectional view thereof taken along line 6-6 shown in FIG. 2.

The portions of the syringe plunger shown in broken lines form no part of the claimed design. Indicia shown in broken lines having a dash-dot-dash format is used to indicate a boundary of the claimed design.
